ATTACHMENT FOR BOTTLE CARRYING
CASES

Joel C. Brodnax, Jr., Peoria, Ill.

Application January 17, 1947, Serial No. 722,537

1 Claim. (Cl. 217—19)

1

This invention has reference to cases for carrying bottles. Said invention has to do particularly with certain attachments for said cases.

The main object of the invention is to provide an attachment for a bottle case or carrier which may be both for strengthening the case itself and providing a replacement for missing parts of certain partitions.

Again, an object is that where a carrying case employed for storage and delivery of bottled goods, such as beverages, for example has lost parts of its usual partitions, to provide a sturdy, easily applied attachment to replace the lost parts to the end that proper conditions are restored.

Other objects and advantages will be apparent in the following specifications aided by the appended drawing forming part hereof.

Figure 1 is a plan of a bottle carrying case to which the device of this invention is applicable.

Figures 2 and 3 are respectively a longitudinal section and a transverse section, in respect to Figure 1, both being in elevation and produced on a larger scale.

Figure 4 shows in perspective parts of two connected attachment portions of the invention.

Figure 5 is also a perspective view of a form corresponding to Figure 4 with slight modifications.

Figure 6 is an elevation of parts of certain partitions of the carrying case of Figures 1, 2 and 3 said parts lying in juxtaposition.

Figure 7 is a perspective view of a single portion of the invention somewhat the same as a part of Figure 5.

Figure 8 is an enlarged detail in perspective of certain partitions in their usual positions with respect to each other and showing the portion of Figure 7 in position on one of such partitions, and

Figure 9 is a vertical transverse section of a partition together with an attachment portion shown attached to a second partition.

Prior to setting forth the construction and positioning of the attachment it may be stated that, as is known, carrying cases for bottled goods, are customarily furnished with partitions crossing each other to provide separate cells for the several bottles. These cases receive rough treatment during handling and when loaded approximate a weight of thirty-eight pounds each.

Although the cases are provided with ready means for grasping them to facilitate handling, the attendant finds that by grasping one or two of the bottle-necks as they protrude from the relatively long and narrow case he has better

2

command than when using the grasping means mentioned.

Knowing that the load is more under control by grasping the bottles the attendant also finds that by holding bottles lying near one end of the case he can rest the other end of the latter upon his hip in a convenient and comfortable manner. Naturally, the bottles lie somewhat loosely in their cells, and due to the leverage placed upon them by the extreme load the effort of the attendant to support such load forces the held bottles against adjacent partitions with disastrous results, in that the latter are broken away even though their ends are "let into" the partitions lying at right angles thereto.

Such a result many times renders a case unusable and requires reconstruction in many instances.

The purpose of the invention is to furnish a sturdy and easily attached member to a partition adjacent a damaged partition and above the same as will now appear.

In the figures of the drawing the bottle carrying case is denoted at 1, being relatively long and narrow, while its longitudinally extending partitions are denoted at 2 and the lateral partition at 3, it being noted that the ends of the latter, as in common practice, are let into the side of the partition 2 as best shown in Figure 8, it being observed, also, that the longitudinal partitions 2, Figures 6 and 8 are made to lie in slots 3' of the transverse, or laterally extended partitions 3, the latter being thus severed for a considerable distance in their height.

Referring to Figure 1, again, two bottles are indicated seated in their cells near one end of the case, these for example, showing the ones grasped by an attendant to support the load, while the opposite end of the case rests against his body; an under-arm-carrying procedure. The said load is carried to a great extent by the bottles grasped, which, in turn is transmitted by the bottles to the partition 3, or those portions of the latter lying between the partitions 2.

In providing the slots 3' of the partitions 3 for the reception of the partitions 2 the former are weakened and although the parts of said partitions 3 are held in the sides of the partition 2 the load imposed is sufficient to break away portions of the partition 3 as suggested at a in Figures 2, 8 and 9. Since the grain of the wooden partition must, and does, parallel the longest measurement thereof it is clearly evident that a fracture may readily occur.

In order to provide a quick means of replacing

the portion broken away, and to restore the case to immediate use, without rebuilding operations, a U-shaped member 4 is provided as shown in Figures 7, 8, 9, particularly, where, for example, if a part of the partition 3 lying between two partitions 2 is destroyed. This member is constructed of heavy sheet metal as a stamping, and in U-form shown, each limb or cheek having at each end a turned flange or wing 5 lying at right angles to the plane of such limb, the overall length of the member being such as to snugly span the space between two partitions 2 and in position to replace the missing broken-away portion of the partition as in Figure 8, the flanges 5 being fixed to the said two partitions as by nailing or by the use of screws. Due to its semitubular form and the manner of securing it in position great pressure may be brought to bear thereon without dislodging it or deforming, and it lies the full height of neighboring partitions.

This form of member is repeated in Figure 5 wherein a strip of material may have several members 4 connected by portions 6, which portions may have the laterally extending ears 7 for attachment by nailing to the tops of the partition 2. In this form, also, the flanges or wings 5 correspond to the described flanges 5. Such a form may provide for strengthening the case in its narrow measurement as shown in Figures 1 and 3, the ends 8 of the structure being secured to the top edges of the sides of the case. This form besides preserving the case for long life likewise, of course, strengthens and protects each of the cell portions of the partitions 3 against any damage thereto however roughly the case may be treated.

In Figure 4 the same structure as that in Figure 5 is provided, at 9 and for a like purpose, except that the flanges 5, 5' of both Figures 5 and 7 are not necessarily used, relying upon the strength of the formed metal train of parts and the securing of the ears 7' to the partition 2 in the same manner as the ears 7.

Naturally, one of the members 9 of Figure 4 may be severed from the train of members while retaining at each end the ears 7', and such member, due to the strength of the metal of which it is formed and a good manner of fixing said ears to the partition 2 may answer in the place of the form of Figure 7 for a single cell although the latter form would perhaps be preferable, where said ears are employed.

In any of the forms shown the U-shaped members depend from their arcuate top portions a considerable distance downwardly into the cells while fully spanning the space between the partitions 2 resulting in a rugged protecting arrangement, while adding long life to the cases and without the necessity of repeated reconstruction thereof.

While the attachment provides two cheek portions each lying at one side of a partition 3, but one of such portions placed at that side of the latter receiving the bottle pressure upon it, provided use is made of the reinforcement offered by such as the rounded top yoke portion, in which event the wings of such single portion properly secured to the partition 2 may serve to withstand the imposed strain.

I claim:

10 In combination with a bottle carrying case having cross partitions therein forming separate cells, a U-shaped member adapted to be inverted upon the position of a broken partition as a replacement of a missing part thereof, the yoke portion of said member lying substantially in line 15 with the tops of all of the named portions, the cheeks of said member depending a considerable distance into a cell along said partition and spanning the space between two adjacent partitions between which the first named partition lies, extensions on the yoke portion by which to affix the latter to each of two spaced partitions, and a flange at the end of each cheek for attachment to said two adjacent partitions.

JOEL C. BRODNAX, JR.
